DISPOSABLE DIAPER

Robert J. Brandl, St. Paul, Minn.

Application May 6, 1946, Serial No. 667,654

3 Claims. (Cl. 128—284)

1

My invention relates to an improvement in disposable diaper wherein it is desired to provide a diaper formed of paper or the like.

The object of the present invention is to provide a diaper which may be used once and disposed of. My diaper may be made at low cost and will act to eliminate the necessity of washing the diapers at frequent intervals.

A feature of the present invention resides in the provision of a diaper having a body of paper having the property of absorbing considerable amounts of liquid. This body is preferably provided on its outer surface with a layer of relatively more moisture-proof paper. This latter layer of paper increases the tensile strength of the diaper to a considerable extent and forms a protection for the absorbent paper body.

A feature of the present invention resides in the provision of a diaper designed with a band to encircle the body of an infant and a second band designed to extend between the legs of the infant from the back to the front thereof. This second band engages the ends of the body encircling band to hold the diaper in place.

A feature of the present invention resides in the manner of holding the diaper in place. The ends of the body encircling band overlap and are provided with registering slots. The second band is designed to pass through these slots and thus lock the diaper in position.

These and other objects and novel features of my invention will be more clearly and fully set forth in the following specification and claims.

In the drawings forming a part of my specification:

Figure 1 is a perspective view of a diaper showing my new construction.

Figure 2 is a diagrammatic view of the diaper in flat form.

Figure 3 is a perspective view of my diaper in folded condition showing a modified manner of attaching the diaper in place.

Figure 4 is a cross sectional view through the diaper shown in Figure 3, the position of the section being indicated by the line 4—4 of Figure 3.

Figure 5 is a sectional view through a portion of the diaper showing the relatively absorbent and relatively non-absorbent layers of which the diaper is formed.

The diaper is constructed as best illustrated in Figure 2 of the drawings. A band 10 is provided connected to the diaper body 11. The band 10 is composed of two oppositely projecting

2

strap portions 12 and 13 which are designed to extend about the sides of the infant and to overlap in the front of the body. Slots 14 and 15 are provided in the band 10 near the extremities thereof.

The diaper body 11 is designed to extend downwardly from the band 10 and to pass between the legs of the infant. The body 11 is of sufficient width to cover a relatively wide area at the rear of the infant. The relatively wide body portion in folded form of the diaper extends substantially to the lower edge of the band 10 at the front of the body when the diaper is in place.

The body 11 extends at substantially right angles to the band 10 and a strap 16 extends integrally from the end thereof. This strap 16 is designed to hold the body portion 11 in proper position by extending through the slots 14 and 15. The slots 14 and 15 are of a width 17 somewhat greater than the width 19 of the strap 16 to simplify the attachment of the diaper.

The diaper may be attached either in the manner illustrated in Figure 1 of the drawings or in the manner shown in Figure 3. In Figure 1 the strap end 12 overlaps the strap end 13 so that the slots 14 and 15 are in substantial registry. The strap 16 is then forced through the slots 14 and 15 and drawn upwardly until the body portion 11 extends close to the lower edge of the band 10. The extremity of the strap 16 is then folded downwardly to overlie the overlapped ends of the band 10, the extremity of the strap 16 being tucked between the band 10 and the attached end of the strap or band 16. In other words, the strap 16 is pulled through the slots 14 and 15 until the diaper is in place and the end of the strap 16 is then folded downwardly and tucked under the attached end of the band 16 near the body 11.

Figures 3 and 4 of the drawings show a slightly different way of attaching the diaper in place. In this arrangement the strap 16 is tucked through the slots 14 and 15, drawn upwardly and interiorly of the ends of the band 10, folded down to overlie the slots 14 and 15 again and the end of the strap again tucked through these slots. This arrangement is clearly illustrated in Figure 4 of the drawings.

The diaper is preferably formed of extremely soft absorbent paper of a type now manufactured and used. This absorbent material is capable of holding considerable quantities of liquid. This absorbent material may comprise a single 55 ply of absorbent material of any desired thick-

3
ness to absorb the required moisture. If desired, however, the paper may comprise a sheet formed of a considerable number of plies of absorbent paper to produce the desired thickness. This latter structure is more conventional and is desirable because of its flexibility and greater absorption. In Figure 5 of the drawings the absorbent body is indicated by the numeral 20. This body is adhered or otherwise affixed to a sheet 21 which is relatively less absorbent and which is of considerably greater tensile strength. The sheet 21 is designed to form a cover for the absorbent body sheet 20 and also to increase the strength of the diaper.

As previously described the slots 14 and 15 are somewhat greater in length than the width of the strap or band 16. In attaching the ends of the band 10 together it is usual practice to overlap the ends 12 and 13 so that the slots 14 and 15 register. The band 16 may then be readily tucked through the registering slots and pulled upwardly along the inner surface of the band. During this procedure the ends of the band 10 are held in proper relationship. As soon as the ends of the band 10 are released the band expands somewhat so that the end of each slot nearest the adjacent end of the band moves into engagement with one side of the strap or band 16. Thus while the diaper is simple to attach because of the length of the slots 14 and 15, the slots will only be in registry a length equal to the width of the band 16 after the diaper has been fastened.

In accordance with the patent statutes, I have described the principles of construction and use of my disposable diaper, and while I have endeavored to set forth the best embodiments thereof, I desire to have it understood that obvious changes may be made within the scope of

10 the following claims without departing from the spirit of my invention.

I claim:

- 5 1. A diaper including a band designed to encircle the body of an infant, a body portion extending at substantially right angles to said band, slots in said band near each end thereof, and a projecting part on said body portion being designed to extend through said slots to hold said band in place.
- 15 2. A diaper including a band designed to encircle the body of an infant, slots in said band near each end thereof, a body portion extending at substantially right angles to said band from a point near the center thereof, and strap means in said body portion designed to extend through said slots to hold said diaper in place.
- 20 3. A diaper including a band having slots near the ends thereof, the ends of said band being arranged in overlapping relation with said slots at least partially in registry, a body portion on said band extending at substantially right angles thereto, and strap means on said body portion extending through said slots and folded over the 25 upper edge of said band.
